UNITED STATES PATENT OFFICE.

WILLIAM VREELAND BERGEN, OF HILLSBORO, OREGON, ASSIGNOR OF ONE-HALF TO
ARTHUR C. SHUTE, OF HILLSBORO, OREGON.

SIGNALING DEVICE.

1,399,923.

Specification of Letters Patent. Patented Dec. 13, 1921.

Application filed March 18, 1920. Serial No. 366,728.

To all whom it may concern:

Be it known that I, WILLIAM V. BERGEN, a citizen of the United States, and a resident of Hillsboro, in the county of Washington and State of Oregon, have invented 5 certain new and useful Improvements in Signaling Devices, of which the following is a specification.

My invention is an improvement in signaling devices, and has for its object to 10 provide a device of the character specified, adapted to be arranged along highways for indicating danger or the need for caution, wherein a visual signal is provided capable 15 of being seen in day-light and having means for illuminating the same through the reflection of the headlights of an on-coming car to be visible at night.

In the drawings:

20 Figure 1 is a front view of the improved signal,

Fig. 2 is a side view,

Fig. 3 is an enlarged section through the illuminating device.

25 In the present embodiment of the invention a suitable standard is provided, in the present instance, a pipe 1 of suitable cross section, preferably having at the top a cap 2 and suitably anchored in the ground. 30 Near the top of this cap there is provided a plate 3 secured to the pipe by any suitable means, indicated at 4, and this plate carries warning legends indicated at 5, in the present instance, the words "Slow down" and 35 "Right turn."

Below the plate 3 is arranged a casing consisting of a parabolic portion 6 and a flaring portion 7. This flaring portion has at its free edge a marginal flange 8, and 40 to this flange there is secured a ring 9 by means of bolts and nuts 10, and the ring carries the head and shaft of the representation 11 of an arrow extending transversely of the post.

45 The head and shaft of the arrow carry a legend indicated at 12, being in the present instance, "Safety first." A lens 13 is supported in the casing 6-7 by means of a bezel ring 14 which engages the edge of the 50 lens and has legs 15 connected with the casing. This lens is supported in such manner that the image of lights approaching the signal will be focused on the portion 6 of the casing which is a reflector, and suit-

ably silvered or otherwise polished on its 55 inner surface.

It will be understood that this lens is ruby red, and the image of the approaching lights will act as an illuminating means for illuminating the lens to attract the notice of 60 drivers of vehicles approaching the signal. By actual test the light can be easily seen at a distance of 600 ft. and it is of especial advantage in that it requires no attention whatever, while it is always ready to show 65 a warning light when the signal could not otherwise be seen.

The signals are arranged at suitable points, and they will act without further attention. The reflecting surface of the 70 parabolic portion of the casing should be rust-proof and capable of withstanding all kinds of weather, and the parts must be so proportioned that the image may be sharp on the reflector. The face of the ring 9 75 provides a surface upon which may be arranged advertising matter of any desired character, and this surface as well as the legends on the plates 3 and the arrow will be of baked enamel. 80

I claim:

A signal of the character specified, comprising a standard or support, a conical shell secured to said support, said shell flaring forwardly and outwardly and surrounded on its outer edge by a vertical ring adapted to carry traffic indicia, the flared portion of said shell presenting an annular light ray collecting and deflecting plane surface, said conical shell having its apex portion curved to define a parabolic reflecting surface, a lens held at the focus of said parabola, the diameter of said lens being less than the diameter of the parabolic area and spaced forward of the vertical plane of the juncture of the flared and parabolic portions of the shell, whereby an annular passage is defined between the lens and the shell to permit passage of light rays from the headlight of the approaching vehicle device, which have been collected and deflected by the plane surface of the shell into the parabolic reflector and also received and reflected by the parabolic reflector to be reflected forwardly through the lens to the 95 approaching vehicle. 100 105

WILLIAM VREELAND BERGEN.
